CLAIM

The ornamental design for a spacer block, as shown and described.

DESCRIPTION

FIG. 1 is a front perspective view of a design of the spacer block;

FIG. 2 is a top plan view of the spacer block of FIG. 1;
FIG. 3 is a bottom plan view of the spacer block of FIG. 1;
FIG. 4 is a first side elevation view of the spacer block of FIG. 1;

FIG. 5 is a second side elevation view of the spacer block of FIG. 1;

FIG. 6 is a front elevation view of the spacer block of FIG. 1; and,

FIG. 7 is a rear elevation view of the spacer block of FIG. 1.

The features shown in broken lines depict environmental subject matter only and form no part of the claimed design.

1 Claim, 5 Drawing Sheets
